UNITED STATES PATENT OFFICE.

THOMAS JEFFERSON KINSER, OF CLAIRFIELD, TENNESSEE.

AERIAL TORPEDO.

1,305,120.

Specification of Letters Patent. Patented May 27, 1919.

Application filed July 24, 1918. Serial No. 246,574.

To all whom it may concern:

Be it known that I, THOMAS J. KINSER, a citizen of the United States, residing at Clairfield, in the county of Claiborne and State of Tennessee, have invented new and useful Improvements in Aerial Torpedoes, of which the following is a specification.

This invention relates to aerial torpedoes, the object in view being to provide a master 10 torpedo embodying propeller means and directional means, and one or more series of relatively smaller torpedoes, carried by the master torpedo and adapted by suitable automatic means to be dropped successively or 15 one after the other and at intervals during the flight of the torpedo, the latter being finally destroyed with disastrous effect upon the enemy when it comes in contact with any obstruction, such as the ground or a 20 building.

With the above and other objects in view, the invention consists in the construction, combination and arrangement of parts, as herein described, illustrated and claimed.

25 In the accompanying drawings:

Figure 1 is a side elevation of the torpedo.

Fig. 2 is a horizontal longitudinal section through the same.

30 Fig. 3 is a vertical cross section on the line 3—3 of Fig. 2.

Fig. 4 is a fragmentary perspective view illustrating the bomb tripping mechanism.

Fig. 5 is a fragmentary plan view of the 35 machine.

The torpedo comprises a shell or casing 1 of streamline formation so that the torpedo may be propelled through the air with small head resistance. The propelling mechanism comprises an engine 2 which is housed 40 within the shell 1 and which actuates a tractor screw propeller 3, the shaft 4 of which is journaled in bearings in the nose portion of the shell 1.

45 At the rear of the shell 1 directional vertical and horizontal rudders 4 and 5 are provided, said rudders being ordinarily fixed so as to cause the torpedo to follow a direct course. In order to obtain the necessary pro-

50 peller speed, the crank shaft 6 of the engine has fast thereon a gear 7 which meshes with and drives a pinion 8, on a counter shaft 9. Fast on said counter shaft 9 is another gear 10 which meshes with a pinion 11 on the pro-

55 peller shaft 4. The propeller is thus driven

at a much higher speed than the engine shaft.

The engine also drives the bomb tripping mechanism and for that purpose the crank shaft 6 has fast thereon a pinion 12 which 60 meshes with and actuates a gear 13 fast on a counter shaft 14. Fast on the same countershaft 14 is a pinion 15 which meshes with and actuates a gear 16 fast on another short countershaft 17. The shaft 17 has fast 65 thereon a pinion 18 which meshes with another gear 19 and the latter has fast on the shaft thereof a pinion 20 which drives a gear 21, the latter in turn meshing with and driving another gear 22 mounted on a short 70 shaft 23 which is connected by a universal joint 24 to the forward end of one of a pair of threaded bomb tripping shafts 25. The shafts 25 extend longitudinally of the shell 1 and follow the general streamline shape 75 thereof, said shafts 25 converging from their front toward their rear ends as shown in the plan view. Each of said shafts 25 constitutes in effect a feed screw which engages a bomb tripping member 26 having a threaded portion 27 which engages the respective feed screw or shaft 25 and moves longitudinally of said screw as the latter is rotated. The feed screws or shafts 25 are connected 80 together for equal and simultaneous rotation 85 in opposite directions by gears 28 fast on the rear ends thereof and of equal size, the rear sections of the shafts or screws 25 being connected to the main sections of the respective shafts by universal joints 29.

Extending along the opposite sides of the shell of the torpedo are bomb supporting racks or rails 30, each of which is formed with a series of slots 31. Arranged adjacent to each of the slots 31 is a bomb holding device comprising a fixed jaw 32 which is secured fixedly to the rail or track bar 30 by fastening means 33, the holder also comprises a movable jaw 34 which is connected by means of a pivot 35 to the fixed jaw 32. 100 The pivoted jaw 34 comprises an arm 36 which extends upwardly through the adjacent slot 31 so that the upper extremity of said arm 36 lies in the path of the bomb tripping member 26 above referred to. The 105 bomb holder supports a bomb 37 having a supporting shaft 38 at the top thereof, said shank having an enlargement or knob 39 which is ordinarily held between the fixed and movable jaws of the bomb holder, until 110

- the tripping member 26 strikes the arm 36 of the pivoted jaw of the holder, whereupon said pivoted jaw is rocked out of its holding position and the bomb is released and permitted to drop. The bomb tripping member 26 moves longitudinally the whole length of the bomb supporting rail or track bar and thereby trips and releases the bombs one after another. It will also be observed that 10 the bomb tripping member 26 at one side of the torpedo moves in the opposite direction from the corresponding member at the opposite side of the torpedo. By omitting the required number of bombs along the initial 15 part of travel of the bomb tripping members, the master torpedo may proceed the required distance from its point of launch before it begins to release and drop the bombs carried thereby.
- 15 The torpedo also comprises a central longitudinally elongated compartment 40 in which an explosive is placed to obtain the final destruction of the master torpedo and to spread disaster among the enemy. 41 20 designates a battery which will connect with a switch and plug for the purpose of igniting and firing the explosive charge in the compartment 40. Extending from opposite sides of the fuselage are aerial supporting 25 wings 42. Inwardly converging stays 45 are attached at their outer extremities to the outer portions of said wings and are connected at their inner ends to oppositely arranged rings 43 which are normally engaged 30 by retaining hooks 44 on the fuselage. The hooks 44 are connected by one or more cords or strands 46 to a switch operating lever 47 which lever when released by the relaxation of the cord or cords 46 operate to close the 35 battery circuit. This result takes place when the master torpedo, after having discharged all of the smaller torpedoes, strikes an object, causing a quick pull on the wires or stays 45.
- 40 I claim:—
- 45 1. In an aerial torpedo, the combination of a master torpedo, a main explosive charge therein, an aerial supporting surface for said shell, directional means, propelling means 50 including an engine housed within said shell, a torpedo supporting rail extending longitudinally of the torpedo shell, torpedo holding members arranged in series along said rail, a torpedo tripping member movable longitudinally of said rail for tripping the torpedo holder and releasing the torpedoes successively, said torpedo tripping member being oppositely connected with and actuated 55 by said engine, electric ignition means for firing said charge including a battery and a switch, and contact wires arranged exteriorly of said shell and adapted upon impact with an object to throw said switch. 60
2. In an aerial torpedo, the combination of a master torpedo body, aerial supporting means therefor, directional means, a tractor screw propeller, an engine housed within the shell of the torpedo and operatively geared to said propeller, torpedo supporting rails extending longitudinally of said shell at opposite sides thereof, feed screws also extending longitudinally of and within the torpedo shell, and geared together for simultaneous and equal rotation in opposite directions, one of said feed screws being 70 geared to and actuated by said engine, torpedo holding members arranged along said supporting rails, torpedo tripping members actuated by said feed screws and movable along said supporting rails for successively 80 tripping said torpedo holders and releasing the torpedoes held thereby, an explosive charge in said shell, electric ignition means for firing said charge including a battery and a switch, and contact wires arranged exteriorly of said shell and adapted upon impact with an object to close said switch. 85
3. In an aerial torpedo, the combination of a master torpedo body, aerial supporting means therefor, directional means, a tractor screw propeller, an engine housed within the shell of the torpedo and operatively geared to said propeller, torpedo supporting rails extending longitudinally of said shell at opposite sides thereof, feed screws also extending longitudinally of and within the torpedo shell, and geared together for simultaneous and equal rotation in opposite directions, one of said feed screws being 90 geared to and actuated by said engine, torpedo holding members arranged along said supporting rails, torpedo tripping members actuated by said feed screws and movable along said supporting rails for successively 95 tripping said torpedo holders and releasing the torpedoes held thereby, an explosive charge in said shell, electric ignition means for firing said charge including a battery and a switch, and contact wires arranged exteriorly of said shell, and adapted upon impact with an object to close said switch, said wires forming stay wires for the aerial supporting 100 means. 105
- 55 In testimony whereof I affix my signature.
